(57) **CLAIM**

The ornamental design for a golf putting exercising apparatus, as shown and described.

DESCRIPTION

FIG. 1 is a perspective view of a golf putting exercising apparatus showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is a perspective view thereof in a using state.

The broken lines in FIGS. 4 and 8 show portions of the golf putting exercising apparatus that form no part of the claimed design. The broken lines in FIG. 9 show portions of the golf putting exercising apparatus and environment that form no part of the claimed design.

1 Claim, 9 Drawing Sheets
